UNITED STATES PATENT OFFICE.

JOHN ROY STARK, OF RACINE, WISCONSIN, ASSIGNOR TO WEBSTER ELECTRIC COMPANY, OF RACINE, WISCONSIN, A CORPORATION OF WISCONSIN.

IGNITION MAGNETO.

1,407,099.

Specification of Letters Patent. Patented Feb. 21, 1922.

Application filed August 25, 1920. Serial No. 405,957.

To all whom it may concern:

Be it known that I, JOHN ROY STARK, a citizen of the United States, and resident of Racine, in the county of Racine and State of Wisconsin, have invented a certain new and useful Improvement in Ignition Magnetos, of which the following is a full, clear, concise, and exact description, reference being had to the accompanying drawings, forming 10 a part of this specification.

My invention relates to ignition magneto and briefly stated, the principal object of the invention is the provision of a magneto of this type, the several parts of which are so constructed, disposed and arranged that the over-all length of the magneto is reduced to a minimum, at the same time providing ample bearing surface for the armature trunnions. The over-all length of the particular 15 magneto construction herein shown is quite small but the armature trunnion bearings are nevertheless considerably larger than the bearings which are quite generally employed in connection with machines of even greater 20 length.

At the present time the rather limited space for ignition magnetos on the engines with which they are employed, has created a demand for magnetos of small size and 25 particularly of small over-all length. In meeting this requirement, manufacturers of ignition magnetos have quite generally resorted to the expedient of reducing the length of the armature trunnion bearings. 30 This expedient is not good practice because unless the armature trunnion bearings are sufficiently long, no magneto will operate satisfactorily for any considerable length of time. I have found that the best practice 35 requires that the armature trunnion bearings should be even larger than those commonly employed heretofore. With these considerations in mind, I have evolved a magneto construction comprising extremely long armature 40 trunnion bearings, which bearings, however, are so disposed that they lie in space from which the bearings have been excluded in prior magneto constructions, enabling me materially to reduce the over-all length of 45 the machine despite the fact that I have increased the length of the armature trunnion 50 bearings.

Other objects of the invention will appear as the following detail description progresses.

In the accompanying drawings illustrating my invention,

Figure 1 is a vertical sectional view of a magneto embodying the improvements of my invention. 60

Figure 2 is a rear elevational view thereof with a portion of the cap associated with the removable end plate broken away.

Figure 3 is a top plan view of the magneto. 65

Figure 4 is a front elevational view thereof.

Figure 5 is a vertical sectional view taken on the line 5—5 of Figure 1, and

Figure 6 is a fragmentary sectional view indicating the manner in which the distributor spool is attached to its associated armature disc. 70

Similar characters of reference refer to similar parts throughout the several views.

The magneto shown comprises field magnet 10 and the field frame or magneto housing 11, the latter being provided with suitable pole pieces, not shown, which pole pieces may be of any suitable construction but are preferably of the type shown and described 75 in my co-pending application, Case 10, Serial No. 405,959, filed of even date herewith.

One end of the housing 11 is formed integral therewith and is provided with a hollow inwardly projecting boss 12 which constitutes a bearing for one of the armature trunnions. The other end of the housing is closed by the removable end plate 13 which is provided with an inwardly projecting hollow boss 14 which constitutes an armature 80 trunnion bearing. The plate 13 is provided at its upper portion with an opening 15 to afford ready access to the interrupter mechanism presently to be described. The opening 15 is normally closed by a cap 16 which 85 is held in position by a leaf spring 17. One end of the spring 17 is firmly held under the head of one of the screws wherewith plate 13 is fastened to the housing 11 while the free end of spring 17 bears against the outer end 90 of a pin 18. The pin 18 projects through the cap 16 and has its inner end attached to a disc 19 of good conducting material. The disc 19 co-operates with a spring-pressed 95 plunger 20 which is carried in a recess in the adjacent armature trunnion. This plunger 20, disc 19, pin 18 and spring 17 serve effectively to ground the armature to the magneto framework. It will be noted that 100 the end plate 13 is provided with a strip of 105

plastic material.

felt indicated at 13^a which effectively prevents the ingress of dust between the end plate and the cap.

The armature structure is provided with 5 the trunnions 21 and 22 which are respectively journaled in the bearing bosses 12 and 14.

The bearing bosses are preferably provided with linings of a material that will 10 wear well against the steel armature trunnions. These linings are conveniently in the form of brass tubing indicated at 12^a and 14^a. The bearing for armature trunnion 21 is conveniently lubricated from a suitable 15 oil well 23 and the bearing for the trunnion 22 is lubricated from a similar oil well 24.

While the specific construction of the armature is not particularly important so far as my present invention is concerned, I 20 prefer to employ the type of armature shown and described in my co-pending application, Case 9, Serial No. 405,958 filed of even date herewith. This form of armature comprises, in addition to the trunnions 21 and 22, the 25 core 23^a carrying primary and secondary windings, the segmental blocks 24^a—24^a which lie at the sides of the ends of the core, and the discs 25 and 26. It will be seen that the trunnions are fixed to the discs 30 25 and 26 and that these discs, the blocks 24^a—24^a and the core 23^a are riveted or otherwise rigidly fastened together. The usual condenser is indicated at 27 and is 35 preferably carried on the inner face of the disc 25.

Disposed immediately adjacent the armature disc 26 is the distributor spool 28. This spool is formed of insulating material and is provided with a conducting ring 29. As 40 is clearly shown in Figure 6, the spool 28 is provided with a pair of studs indicated at 30 and 31. These studs fit snugly in the apertures in the disc 26 and are held therein by U-shaped spring clips 32—32. These 45 clips engage in annular grooves in the studs and prevent the withdrawal of the studs from the disc 26. It will be noted that stud 31 furthermore constitutes a conduit through which one of the terminals of the secondary winding is lead to the conducting ring 29.

The central opening through spool 28 is substantially greater than the greatest diameter of the bearing boss 12 so that the spool may lie around the said boss as is 55 clearly illustrated in Figure 1. It will be noted that there is but a very slight clearance between spool 28 and the adjacent end of the housing. The bearing for trunnion 21 is considerably longer than the trunnion 60 bearings usually found in magnetos of this general type but this exceptionally long trunnion bearing does not necessitate elongation of the magneto as a whole for the reason that the major portion of the bearing 65 lies within the spool 28.

The conducting ring 29 co-operates with a spring-pressed brush 33 carried in the block 34 of any suitable insulating material. Electrically connected with the brush 33 and extending from the block 34 is the high 70 tension lead 35 through which the ignition current is supplied to the spark plug of the engine with which the magneto is associated. The base of the block 34 is preferably rectangular in shape so that the block may be 75 placed in either of two positions in a correspondingly shaped recess in the top of the housing 11. By virtue of this arrangement, the high tension lead 39 may be caused to project from either side of the magneto. 80 Block 34 is held in position by the free end of a leaf spring 36, the other end of which is clamped to the top of the magneto housing by a suitable screw as illustrated in Figure 1.

My present invention, as herein illustrated, is applied to that type of magneto known in the trade as a high tension oscillator. However, my invention is not limited to use with this particular type of magneto machine. It will be understood, of course, 85 in an adaptation of my invention to a rotary ignition magneto for a multiple cylinder engine, the spool 28 will be provided with a distributor segment which would successively contact with brushes connected with 90 the several spark plugs of the engine in a well-known manner.

I have explained how the distributor devices are grouped around the bearing boss 12. I will now explain how, for a similar 100 purpose, the interrupter devices are distributed around the boss 14. Carried by the disc 25 and insulated therefrom in the usual manner is a plate 37 one end of which is turned at right angles to the plane of the 105 disc to over-lie the bearing boss 14 and is provided with the fixed interrupter contact 38. Plate 37 is, of course, electrically connected with the insulated terminal of the primary winding in the usual manner. 110 The other interrupter contact, indicated at 39, is mounted upon the free end of the interrupter arm 40, the other end of which is pivoted to the disc 25 and is electrically connected therewith. A leaf spring 40^a normally urges the contact 39 into engagement with the contact 38. The particular construction of the interrupter devices carried by the armature is not particularly important but it is extremely desirable that these 120 parts lie around the armature bearing boss 14 so that the inner end of the bearing 14 may lie immediately adjacent the armature disc 25 as shown in Figure 1. The interrupter arm 40 is provided with a block 41 125 which co-operates with the annular cam 42. Cam 42 is disposed around and keyed upon bearing boss 14, the boss being provided with a portion of reduced diameter for the reception of the cam as is clearly illustrated 130

in Figure 1. It will be understood, of course, that in the particular arrangement shown that when, upon the cocking movement of the armature, arm 41 rides up on the flattened surface of the cam, the contacts are permitted to engage, separation of the contacts being effected when, upon the recoil of the armature, the block 41 rides out to the position shown in Figure 5.

10 The annular cam 42 is driven to position upon the boss 14 and is held against rotary movement thereon by a Woodruff key 43. In order to provide a means for removing the cam from the parts when desired, a plurality of apertures 44-44 are drilled through plate 13 to a point immediately behind the cam. By inserting a suitable tool into the apertures 44, the cam may be driven off of the boss without injury to either the boss 20 or cam.

It will be unnecessary to illustrate or describe the circuit connections of the apparatus in detail as any approved or suitable arrangement of the circuit connections may 25 be employed.

Since the magneto shown is of the oscillating type, the magneto frame 10 is provided with a pair of arms 45-45 which arms at their extremities are provided with pins 30 46-46 carrying rollers 47-47. Keyed upon the armature shaft is a yoke 48 comprising a push finger 49. Projecting forwardly from the yoke are pins 50-50 whereon are mounted rollers 51-51. The comparatively heavy tension springs 52-52 act between the rollers 47 and 51 and normally tend to hold the armature of the magneto in the position illustrated in Figure 5. In the operation of the machine the push finger 40 49 is, of course, actuated in a well-known manner to cock the armature against the tension of the springs 52. When the push finger is released, the springs quickly return the armature toward normal position.

45 During the recoil of the armature, current is generated in the primary winding, the circuit of the primary winding being interrupted near the end of the recoil movement of the armature by the separation of the 50 interrupter contacts to the end that high tension current may be induced in the secondary in a well-known manner.

While I have illustrated the improvements of my invention applied to a magneto of the oscillating type, it will be understood that 55 those features of my invention which enable me to employ exceptionally long armature trunnion bearings without necessarily in-

creasing the over-all length of the magneto, are equally applicable to rotary magneto constructions.

What I claim is new and desire to secure by Letters Patent is:—

1. A magneto comprising a housing and an armature structure disposed therein, the armature being provided with trunnions, inwardly projecting hollow bosses carried by the ends of the housing, the bosses constituting bearings for the trunnions, a distributor spool carried at one end of the armature structure and rotatable therewith, said spool provided with a central opening adapted to embrace the adjacent boss, interrupter contacts at the other end of the armature structure and a cam for operating 65 said contacts, said cam comprising an annulus disposed around and fixed upon the bearing boss adjacent said contacts.

2. A magneto comprising a housing and an armature structure provided with trunnions mounted therein, the bearing for one of said trunnions comprising an inwardly projecting hollow boss carried by one end of the housing, interrupter contacts carried on that end of the armature structure next adjacent the boss and an annular cam for operating said contacts, said cam being disposed around and secured upon said boss.

3. A magneto comprising a housing and inwardly projecting hollow bearing bosses 90 carried by the ends of the housing, an armature structure disposed in the housing and having trunnions bearing in said bosses, distributor mechanism disposed around one of said bosses and interrupter mechanism disposed around the other boss.

4. A magneto comprising a housing, and an armature structure provided with trunnions mounted therein, the bearing for one of said trunnions comprising an inwardly 100 projecting hollow boss carried by one end of the housing, an interrupter mechanism comprising two relatively movable parts, namely, one part which comprises interrupter contacts and a part which provides 105 the interrupter operating cam, one of the aforesaid parts being carried on that end of the armature next adjacent said boss, and the other part comprising an annulus which is fitted around and fixed upon said boss. 110

In witness whereof, I hereunto subscribe my name this 5 day of August, 1920.

JOHN ROY STARK.
